FLUID BLAST ARC EXTINGUISHING
CIRCUIT BREAKER

Arnold E. Brock, Burlingame, Calif., assignor to
Pacific Electric Manufacturing Corporation,
San Francisco, Calif., a corporation of California

Application August 27, 1945, Serial No. 612,777

7 Claims. (Cl. 200—148)

1

My present invention relates to high voltage circuit breakers, and more particularly to an improved means by which an arc drawn between the circuit controlling contacts of the circuit breaker may be effectively interrupted, irrespective of its current value, by a blast of air or other arc extinguishing fluid and it has for its object to provide an improved arc extinguishing means for circuit breakers of the fluid blast type by which an arc established between the circuit interrupting contacts of the circuit breaker may be effectively and efficiently extinguished, irrespective of its current value, with a minimum of arc extinguishing fluid.

Another object of the invention is to provide an improvement in circuit breakers of the fluid blast type which will prevent the building up of a back pressure by the generation of gases in an arc at the point of contact separation.

Another object of the invention is to provide an arc extinguishing device for use with the circuit controlling contacts of a fluid blast circuit breaker in which means are provided for the venting of any excessive gas pressure that might interfere with the extinction of an arc therebetween at the time of circuit interruption.

A further object of the invention is to provide a new and novel contact arrangement for circuit breakers of the axial blast arc extinguishing type in which one of the contacts is provided with a pressure responsive by-pass or valve means that will operate in the event of a sustained arc to relieve any excessive pressure caused by arc generated gases and permit a substantially normal flow of arc extinguishing fluid through the arc at the time of circuit interruption.

Other objects and advantages of the invention will be evident to those skilled in the art, and pointed out hereinafter in the following description taken in connection with the accompanying drawing, wherein there is shown by way of illustration and not of limitation preferred embodiments of my invention.

In the drawing;

Figure 1 is a fragmentary vertical elevation showing my invention as applied to a circuit breaker of the type employing the so-called axial blast principle for the extinction of any arc established between its contacts upon circuit interruption,

Figure 2 is a fragmentary sectional view taken along line II—II of Figure 1, looking in direction of arrows,

Figure 3 is a similar fragmentary sectional view taken along line III—III of Figure 1,

2

Figure 4 is a fragmentary sectional view showing a modified form of the invention as applied to a circuit breaker of the type employing the so-called transverse blast principle for the extinction of any arc established between the contacts thereof, and

Figure 5 is a fragmentary sectional view taken along line V—V of Figure 4, looking in direction of arrows.

10 The use of a blast of air or other fluid as an arc extinguishing medium in circuit breakers has long been considered, but up to the present time no satisfactory arrangement has been found that will operate successfully under all the various current values at which interruption of a circuit may be necessary. This is believed to be due to the fact that once the circuit breaker has been designed, the physical dimensions of the chamber surrounding the zone of arc interruption become 15 fixed, while at the same time the current values of the arc to be extinguished may vary greatly. In other words, in the prior arrangements the blasts of arc extinguishing fluid employed operate in a substantially uniform manner under all 20 conditions and do not take into account the possible variations in the current values of the arc. As a result, at low current values the blast of arc extinguishing fluid or air is only slightly heated and there is, therefore, established a low pressure 25 area behind the point of arcing between the separating contacts, which hinders arc interruption. This low pressure area also tends to promote a 30 restriking of the arc, due to the fact that it does not permit the building up of sufficient dielectric effect within the blast of arc extinguishing fluid to extinguish the arc. Similarly, when an 35 arc of high current value is interrupted, the arc extinguishing gases are heated to a higher temperature and expand to such an extent that there 40 is often established a reversal of flow of arc extinguishing gases between the separating contacts. This retards the blast of arc extinguishing fluid and results in a high ionization thereof 45 which likewise prevents arc extinction and the ultimate interruption of the circuit.

In view of the above, it has been necessary in the past to compromise between the different operating conditions that result from the interruption of a circuit at different current values. In 50 this direction two methods have been used. The first has been to provide a large volume blast passageway in which the arc is drawn, and the second has been to confine the arc in a restricted chamber having a relatively narrow passageway 55 and provide a large exhaust outlet at or imme-

diately beyond the point of arcing. The first of these methods requires the use of excessive quantities of arc extinguishing fluid, and while the latter method is more economical in the use of the arc extinguishing fluid and has met with some success, it is still open to the objection that a blocking pressure is often built up within the restricted passageway at the point of contact separation that seriously interferes with the free flow of the arc extinguishing fluid through the passageway, which tends to decrease the efficiency of the circuit breaker and lower its maximum current interrupting capacity.

In accordance with the present invention, I provide an arc extinguishing arrangement in which the establishment of such a blocking pressure by the arc generated gases is avoided, and in which a blast of arc extinguishing fluid, having a substantially constant pressure and velocity, may be used at all times regardless of the current value at the time of the circuit interruption. This enables the use of a small volume of the arc extinguishing fluid and also avoids the need for a compromise in performance to meet different conditions of current value at the time of circuit interruption. This operation, with a constant pressure and velocity, regardless of current value at the time of interruption, is obtained in accordance with the preferred embodiment of the invention by providing a fluid blast passageway which is expandable, or in which the velocity and/or volume of arc extinguishing fluid flowing therethrough may vary in response to gas pressures that may result from temperature changes caused by the arc between the separating contacts during circuit interruption. It has been found to be a fact that the interrupting capacity of circuit breakers employing an arc extinguishing fluid blast for interrupting an arc between its contacts is limited by any condition that will permit the generation of excessive heat in an arc drawn between its separating contacts, which will result in a reverse flow of the arc extinguishing fluid through its arc extinguishing chamber. This is true even though the reversal of flow of the arc extinguishing fluid may be only temporary, and often the interrupting capacity of the circuit breaker is limited to a value far below the maximum rated capacity thereof. This is explained by the fact that any reversal of flow or blocking pressure that will interfere with the normal blast of the arc extinguishing fluid through the arc will prevent a proper cooling of the highly ionized gases that are generated in any arc drawn between the separating contacts when a circuit is being interrupted.

In the accompanying drawing, I have shown preferred arrangements, wherein the circuit controlling contacts of a circuit breaker are disposed in arc extinguishing chambers that are provided with pressure responsive or valved relief outlets through which the fluid blast and/or arc generated gas pressure may escape from the zone of arcing and thus prevent the building up of any blocking pressure within the contact enclosing chamber, which might interfere with a normal flow of the arc extinguishing fluid between the separating contacts.

In Figures 1, 2 and 3 of the drawing there is shown, in detail, an embodiment of the invention as applied to a circuit breaker of the so-called axial blast type. In circuit breakers of the axial flow fluid blast type the arc extinguishing fluid is introduced either through one of the contacts to the arcing space formed therebetween upon

contact separation, or the arc extinguishing fluid is charged into a chamber surrounding the separable contacts, so that when the contacts separate, this arc extinguishing fluid may exhaust under pressure axially outward through one of the contacts. The device here shown is of this latter type and, in its preferred form, it contemplates the employment of a substantially cylindrical stationary contact 10 with which an axially movable contact 11 cooperates. The stationary contact 10 has a truncated conical contact surface 12 at its inner end with which a conical contact surface 13, formed upon the contact 11, cooperates. In this way there is provided a restricted throat 14 at the inner end of the contact 10 through which an arc extinguishing fluid may discharge outwardly through the stationary contact 10. As here shown, the contacts 10 and 11 are enclosed within a fluid pressure containing chamber 15 that is formed thereabout by a tubular member 16 which carries suitable end closure members 17. Only one of the end forming members 17 is here shown, but it will be understood that a similar end closure member 17, at the lower end of the chamber 15, will be provided with a packing or stuffing box through which the operating rod or shank of the movable contact 11 may move in a sealed manner. The stationary contact 10 is mounted within the chamber 15 and is secured to the closure member 17 by means of an externally threaded bushing 18 that has a somewhat larger discharge conduit located in alignment with the restricted throat 14 at the inner end of the contact 10. This bushing 18 extends through the end closure member 17 and is secured by means of a threaded conduit forming member 19 which may lead to the atmosphere or to a suitable flame and sound quenching muffler. Within the central opening through the cylindrical stationary contact 10, and also in register with the restricted throat 14 at the inner end thereof, there is an annular valve-like member 20 which has a somewhat more restricted throat-like aperture 21 through which, under normal operating conditions, the blast of arc extinguishing fluid will be discharged. This annular valve-like member 20 is supported for axial movement, with respect to the restricted throat 14, by means of a cage-like support 22 which, as is more clearly shown in Figure 2, has radial arms 23 that hold it centrally within the contact 10. This cage-like member 22 also carries a cylindrical sleeve 24 which is held in spaced relation with the inner wall of the stationary contact 10 by the radial arms 23, so as to form an auxiliary or by-pass conduit 25 through which gases may exhaust when the valve-like member 20 is moved away from the restricted throat or orifice 14 of the stationary contact 10. Mounted within the cylindrical sleeve 24 there is a compression spring 26 which operates to bias the valve-like member 20 in a position against the rim of the restricted throat 14 so that upon contact separation, the blast of arc extinguishing fluid will be caused to normally exhaust through the throat-like aperture 21 thereof. At this point it will be noted that the movable contact 11 is provided with a highly refractory arcing tip 27 which is resistant to pitting and/or burning away in the event of a sustained arcing.

In operation, with the chamber 15 charged with an arc extinguishing fluid, it will be seen that when the moving contact 11 is moved away from the stationary contact 10, as in interrupting a circuit, any arc drawn between the respective con-

tact surfaces 12 and 13 of these contacts will be subjected to a blast of arc extinguishing fluid which will normally exhaust centrally through the throat-like aperture 21 of the valve-like member 20 and outwardly to the atmosphere or a muffler, as above suggested. However, should the current value of this arc be of such a value as would result in excessive heating, and a consequent excessive generation of ionized gases that might set up a blocking pressure at the point of contact separation which would interfere with the free flow of cool arc extinguishing fluid through the arc, the annular valve-like member 20 will be moved upwardly in response to this excessive pressure and thus permit this excessive gas pressure to escape outwardly therearound and to the atmosphere or muffler through the annular auxiliary or by-pass conduit 25. Under normal operating conditions it is anticipated that the arc extinguishing fluid will be maintained in the chamber 15 at a pressure somewhere between 80 and 100 pounds per square inch, and the spring 26 will be so arranged and designed as to permit a valve opening movement of the annular valve-like member 20 whenever the pressure at the restricted throat 14 of the stationary contact 10 approaches to within 50 to 75 per cent of the pressure value normally maintained within the chamber 15. However, these values may vary under different conditions of operation. In an actual test, with contacts constructed as here illustrated, it was found possible, with the valve member 20 set to respond at a pressure of from 40 to 60 pounds per square inch, to interrupt a current of 4000 amperes at 15000 volts within one-half a cycle with an air pressure of 80 pounds, whereas without the annular valve member, an air pressure of 160 pounds per square inch was required to obtain a comparable performance at this current and voltage. Therefore, it is apparent that by controlling the exhaust of hot gases from the arcing zone to the atmosphere or muffler, under conditions responsive to the current values of the arc, a considerable saving in the pressure and quantity of the arc extinguishing fluid results.

Reference is now made to Figures 4 and 5 of the drawing, wherein the invention is shown as embodied in a circuit breaker of the so-called transverse blast type. In circuit breakers of this latter type, the cooperating contacts are generally arranged to separate and draw any arc established therebetween within a relatively narrow arc chute which flares outwardly so as to permit a rapid exhaust and cooling of the fluid blast and arc generated gases. In these figures of the drawing, a stationary contact 28, with which a movable contact 29 is adapted to cooperate, are shown as arranged to engage and disengage each other within a chamber or arc chute forming housing 30. The movable contact 29 is of blade-like configuration, and the stationary contact 28 carries a plurality of yielding contact fingers 31 that engage the opposite sides of the movable contact 29. The stationary contact 28, with its yielding contact fingers 31, is fixed within the chamber of arc chute forming housing 30 and opposite thereto the housing 30 has a relatively small opening 32 through which the moving contact 29 may travel in moving into and out of circuit making engagement with the yielding contact fingers 31 of the stationary contact 28. Immediately above the path of travel of the moving contact 29 there is a fluid directing conduit 33 through which a blast of arc extinguishing fluid may be discharged

into the chamber or arc chute forming housing 30 transversely to the path of any arc that may be established between the moving contact 29 and the yielding contact fingers 31 of the stationary contact 28. Directly opposite to the conduit 33 the arc chute forming housing 30 is flared outwardly, as at 34, so as to provide for the rapid exhaust of the arc extinguishing fluid after it has passed through the path of any arc established between the contacts 28 and 29. To accelerate the breaking up of any persistent arc, the flared portion 34 of the arc chute forming housing 30 is also generally provided with a plurality of spaced and radially extending baffle forming members 35 which operate to break up the arc into smaller segments and thus provide for a more efficient cooling of the hot arc generated gases. Arranged outwardly beyond the flared portion 34 of the baffle forming members 35 within the housing 30, there is a conduit or muffler 36 into which the cooled gases are discharged and finally exhausted to the atmosphere. This arrangement, as so far described, is well known and understood by those skilled in the art, and while it is capable of interrupting circuits at high voltages and current values, it is open to the objection that its current interrupting capacity is limited to a relatively narrow range of current values. This difficulty is believed to be due to the fact that the hot gas confining housing 30 makes no allowances for variations in gas pressures which result from the interruption of a circuit at different current values. In accordance with the present invention, this is overcome by providing the arc chute forming housing 30 with a means that will relieve the arc chute, or the chamber thus formed, about the arcing zone between the separating contacts, of any back pressure that might interfere with the free and effective flow of the arc extinguishing fluid through any arc which may be drawn between the stationary contact 28 and the moving contact 29 in interrupting a circuit. This means, as here shown, may be in the form of an auxiliary vent or exhaust outlet 37 that will permit the escape of arc generated gases from the arc chute at the point of contact separation whenever a back pressure, in excess of that which would prevent an effective flow of the arc extinguishing fluid, occurs. The auxiliary vent or exhaust outlet 37 may be located in one or both sides of the arc chute forming housing 30 and, as is more clearly shown in Figure 5 of the drawing, these auxiliary vents or exhaust outlets 37 are provided with pressure responsive valve members 38 that are yieldingly biased into sealing relation with the auxiliary vents or exhaust outlets 37 by means of springs 39. Preferably, these vents or exhaust outlets 37 are located closely adjacent the point of contact separation where the highest gas pressures are initially generated. The vents or exhaust outlets 37 are shown as disposed in the sides of the arc forming housing 30 adjacent the inner ends of the baffle forming members 35 where an accumulation of hot gases might effectively set up a back pressure that would interfere with, if not entirely stop, the flow of the arc extinguishing gases through the chamber or arc chute forming housing 30. It is believed that the operation of this embodiment of the invention will be clearly understood from the operation above described in connection with the embodiment of the invention shown in Figure 1. Therefore, it appears only necessary to here add that the springs 39, which operate to seat the two valve members 38 within the auxiliary vent or exhaust outlets 37,

here shown as disposed one at each side of the arc chute forming housing 38, may be calibrated or designed so as to permit a response of their respective valve members 38 at different pressure values and, as a result, the arc extinguishing characteristics of the arrangement shown may be rendered effective to extinguish an arc established between the separating contacts 28 and 29 over a wider range of current values.

While I have described and illustrated specific forms of the invention, I desire to have it understood that the invention is not limited to the specific arrangements disclosed, but may be embodied in other ways that will suggest themselves to persons skilled in the art and all such changes as come within the scope of the appended claims are to be considered as part of this invention.

Having thus described my invention, what I claim and desire to secure by Letters Patent is—

1. In a fluid blast arc extinguishing circuit breaker, the combination of a contact enclosing chamber adapted to maintain a fluid under pressure having an exhaust outlet at one end, a stationary contact of cylindrical configuration extending into said chamber and forming a continuation of said exhaust outlet through which a fluid under pressure within said chamber may flow to said exhaust outlet, said cylindrical contact having its inner end formed to provide an open annular contact surface, a cooperating axially movable contact having a cooperating contact surface adapted to engage the annular contact surface of said cylindrical contact and close the opening therethrough, an annular valve-like member disposed within and in back of the annular contact surface of said cylindrical contact having a restricted centrally disposed opening through which a blast of arc extinguishing fluid may flow when said contacts are moved out of engagement with each other, a cylindrical sleeve for supporting said movable valve-like member centrally in spaced relation with the inner walls of the cylindrical contact and forming an outer annular passageway leading to the exhaust outlet of said contact enclosing chamber, and means for yieldingly maintaining said movable valve-like member in position where a blast of arc extinguishing fluid will be normally directed through its central opening and permitting movement thereof in the event of a predetermined arc generated gas pressure to allow the generated gases to flow around the outside thereof and through said annular passageway to the exhaust outlet of said chamber.

2. In a fluid blast arc extinguishing circuit breaker, the combination of a contact enclosing chamber adapted to maintain a fluid under pressure having an exhaust outlet at its end, a stationary cylindrical contact mounted within and forming a continuation of the exhaust outlet of said chamber through which a fluid under pressure within said chamber may flow to said exhaust outlet, said cylindrical contact having its inner end formed to provide a truncated conical contact surface, a cooperating axially movable contact having a conical contact surface adapted to engage the truncated conical contact surface of said cylindrical contact and close the opening therethrough, a movable valve-like member disposed centrally within said cylindrical contact having a centrally disposed and restricted opening through which a blast of arc extinguishing fluid may flow when said contacts are moved out of engagement with each other, means for supporting said movable valve-like member centrally

in spaced relation with the inner walls of the cylindrical contact, and spring means for yieldingly maintaining said movable valve-like member in a position with respect to the truncated conical contact surface of said cylindrical contact where a blast of arc extinguishing fluid will be normally directed through its central opening and permitting movement thereof in the event of an abnormal back pressure due to arc generated gases which will allow said generated gases to flow around the outside thereof and to said exhaust inlet.

3. In a fluid blast arc extinguishing circuit breaker, the combination of a substantially cylindrical contact forming member having an annular contact surface at its end and a passageway extending centrally therethrough for the exhaust of an arc extinguishing fluid, a second contact member adapted to engage said annular contact surface and operating to close the passageway through said cylindrical contact when said contacts are in circuit making engagement with each other, a pressure confining chamber surrounding said contacts at their point of separation adapted to be charged with an arc extinguishing fluid medium under pressure, said cylindrical contact being mounted in a wall of said chamber and forming an exhaust conduit for said arc extinguishing fluid, a passageway dividing means disposed within said cylindrical contact and forming an outer auxiliary passageway therethrough, and a pressure responsive valve means cooperating with said passageway dividing means operating to prevent a flow of said arc extinguishing fluid through said auxiliary passageway under normal arcing conditions and permitting said arc extinguishing fluid to exhaust through said auxiliary passageway under abnormal arcing conditions.

4. In a fluid blast arc extinguishing circuit breaker, the combination of a substantially cylindrical stationary contact forming member having an annular contact surface at its end and a passageway extending centrally therethrough for the exhaust of an arc extinguishing fluid, a movable contact adapted to engage said annular contact surface and substantially close the passageway through said cylindrical stationary contact when said contacts are in circuit making engagement with each other, a pressure confining chamber surrounding said contacts at their point of separation adapted to be charged with an arc extinguishing fluid medium under pressure which will exhaust therefrom to extinguish any arc established between said contacts when they separate to open a circuit, said cylindrical stationary contact being mounted in a wall of said chamber and forming an exhaust conduit for said arc extinguishing fluid, a cylindrical partition forming means disposed within said cylindrical contact and forming an annular auxiliary passageway therein, a pressure responsive valve means cooperating with said cylindrical passageway dividing means operating to prevent a flow of said arc extinguishing fluid through said outer annular passageway under normal arcing conditions and permitting said arc extinguishing fluid to exhaust through said annular passageway under abnormal arcing conditions, said pressure responsive valve means being adapted and arranged to operate and open said auxiliary passageway at a pressure below that which would maintain a blocking pressure of ionized gases sufficient to prevent an extinction of the arc by a flow of said arc extinguishing fluid through said cylindrical contact.

5. In a fluid blast arc extinguishing circuit breaker, the combination of a substantially cylindrical contact having an annular contact surface at one end and a fluid blast exhaust passageway extending centrally therethrough, a movable contact adapted to move axially with respect to said cylindrical contact and close the fluid blast exhaust passageway through said cylindrical contact when said contacts are in circuit establishing engagement with each other, a chamber surrounding said contacts from which an arc extinguishing fluid under pressure may exhaust through said cylindrical contact to extinguish an arc established between said contacts when said contacts separate, means forming an annular concentrically arranged vent passageway within the fluid blast exhaust passageway through said cylindrical contact, an axially movable valve member having a centrally located throat-like opening for the passage of fluid under pressure from said chamber upon separation of said contacts, said annular valve member being positioned to normally close said annular vent passageway, and spring means for maintaining said annular valve member in its vent passageway closing position and adapted to permit axial movement of said annular valve member to open said vent passageway for the escape of ionized gases generated by an arc between said contacts at a pressure below that which would establish an exhaust blocking pressure within the throat-like aperture of said valve member.

6. In a fluid blast arc extinguishing circuit breaker, the combination of a substantially cylindrical contact having an annular contact surface at one end and a fluid blast exhaust passageway extending centrally therethrough, a movable contact adapted to move axially with respect to said cylindrical contact and close the fluid blast exhaust passageway through said cylindrical contact when said contacts are in circuit establishing engagement with each other, a chamber surrounding said contacts from which an arc extinguishing fluid under pressure may exhaust through said cylindrical contact to extinguish an arc established between said contacts when said contacts separate, means forming an annular concentrically arranged vent passageway within the fluid blast exhaust passageway through said cylindrical contact, and axially movable valve member having a centrally located throat-like opening for the passage of fluid under pressure from said chamber upon separation of said contacts, said annular valve member being positioned to normally close said annular vent passageway, and spring means for maintaining said annular valve member in its vent passageway closing position

and adapted to permit axial movement of said annular valve member to open said vent passageway for the escape of ionized gases generated by an arc between said contacts at a pressure substantially corresponding to the pressure of the arc extinguishing fluid flowing between said contacts, whereby a blocking of the flow of arc extinguishing fluid between said separating contacts due to any back pressure at said throat-like opening will be avoided.

7. In a fluid blast arc extinguishing circuit breaker, the combination of a contact enclosing chamber adapted to maintain a fluid under pressure having an exhaust outlet at one end, a cylindrical contact member mounted within and having its central opening communicating with the exhaust outlet of said chamber through which a fluid under pressure within said chamber may flow to said exhaust outlet, said cylindrical contact having its inner end formed to provide an annular contact surface, a cooperating movable contact having a contact surface adapted to engage the annular contact surface of said cylindrical contact member and close the central opening therethrough, an annular valve member disposed centrally within said cylindrical contact having its central opening disposed to form a restricted passageway through which a blast of arc extinguishing fluid may flow when said contacts are moved out of engagement with each other, means for supporting said valve member centrally in spaced relation with the inner walls of said cylindrical contact member, and means for yieldingly maintaining said valve member in a position with respect to the annular contact surface of said cylindrical contact member, where a blast of arc extinguishing fluid will be normally directed through its central opening, but permitting an operation movement thereof, which will allow arc generated gases to flow around it and to said exhaust inlet in the event of an abnormal gas pressure due to arcing between said contacts.
